UNITED STATES PATENT OFFICE

2,367,231

RAILROAD CAR VENTILATOR

Joseph P. Malloy, Washington, Ind.

Application April 28, 1943, Serial No. 484,889

2 Claims. (Cl. 98—19)

The present invention relates to new and useful improvements in railroad car ventilators and has for its primary object to provide, in a manner as hereinafter set forth, a device of this character which is adapted to cause the withdrawal of smoke, odors, foul and warm air from the car while excluding cinders, rain, drafts, etc.

Another very important object of the invention is to provide a ventilator of the aforementioned character comprising a novel construction and arrangement whereby access to the interior of the device may be expeditiously had for maintenance.

Other objects of the invention are to provide a ventilator of the character described which will be comparatively simple in construction, strong, durable, highly efficient and reliable in use, compact, attractive in appearance and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein—

Figure 1 is a view in side elevation, showing a ventilator constructed in accordance with the present invention installed on a railroad car.

Figure 2 is a vertical sectional view, taken substantially on the line 2—2 of Figure 1.

Figure 3 is an elevational view, looking at the inner side of the plate which is attached to the car.

Figure 4 is an elevational view, looking at the outer side of the car attached plate.

Referring now to the drawings in detail, it will be seen that the embodiment of the invention which has been illustrated comprises a substantially rectangular plate 1 of suitable dimensions and material, preferably metal. The plate 1 is provided with apertures 2 which accommodate bolts 3 for firmly securing said plate in position on the panel 4 of a railroad car 5 between the top and bottom decks 6 and 7, respectively, of said car. The plate 1 is mounted on the panel 4 over a circular opening 8 in said panel.

The plate 1 comprises an outwardly pressed central portion 9 having formed therein a circular opening 10 in registry with the opening 8. Mounted on the portion 9 of the plate 1 over the opening 10 is a screen 11. A ring 12 secures the screen 11 in position, said ring, in turn, being secured to the plate 1 by bolts 13. The bolts

13 pass through the marginal portions of the screen 11.

The plate 1 further includes an inclined top 14 and apertured side flanges 15. Depending from the free or outer edge of the top 14 is an integral lip 16. A depending flange 17 is secured beneath the top 14 in spaced, opposed relation to the lip 16.

Removably mounted on the plate 1 is a hood 18 which, as best seen in Figure 2 of the drawings, is open at its bottom. The hood 18 includes an inclined top 19 which terminates in an integral, upstanding flange 20 which is engaged beneath the top 14 between the lip 16 and the flange 17. The hood 18 further includes diagonal side portions 21 having formed integrally therewith apertured flanges 22 which are engageable between the flanges 15 of the plate 1. Bolts 23 detachably secure the apertured flanges 16 and 22 together.

It is thought that the operation of the device will be readily apparent from a consideration of the foregoing. Briefly, as the car travels in either direction, smoke, odors and air therein will be drawn through the openings 8 and 10 and out through the open bottom of the hood 18 in a well known manner. The construction and arrangement is such as to exclude all dirt, cinders, rain, etc., from the car. By simply removing the bolts 23, the hood may be detached to facilitate access to the screen 11 and the interior of the device. The portions 21 of the hood 18 comprise inturned flanges 24 on their upper ends which are secured at 25 to the top 19 of said hood.

It is believed that the many advantages of a railroad car ventilator constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

Having described the invention, what is claimed as new is:

1. A ventilator of the character described comprising a metallic plate for mounting vertically on the panel of a railroad car between the top and bottom decks of said car, said plate including an outwardly pressed central portion having a circular opening therein for registry with an opening in the panel, a screen over the first-named opening, a ring removably mounted on the plate for securing the screen in position thereon, the plate further including an inclined top, an integral lip depending from the top, a flange

mounted beneath the top and depending therefrom in spaced, opposed relation to the lip, vertical side flanges on the plate, and a hood removably mounted on the plate, said hood being open at its bottom and including an inclined top, an integral flange rising from the second-named top and engageable beneath the first-named top between the lip and first-named flange, said hood further including diagonal side portions and flanges integral with said side portions, the last-named flanges being engageable between the second-named flanges, and means for detachably securing said last-named flanges to said second-named flanges.

2. A ventilator of the character described comprising a plate for mounting vertically on the panel of a railroad car between the top and bottom decks of said car, said plate including an outwardly pressed central portion having a circu-

lar opening therein for registry with an opening in the panel, a screen over the first-named opening, means for securing the screen on the plate, said plate further including an inclined top, an integral lip depending from the top, a flange mounted beneath the top and depending therefrom in spaced opposed relation to the lip, vertical side flanges on the plate, and a hood removably mounted on the plate, said hood including an inclined top, an integral flange rising from the second-named top and engageable beneath the first-named top between the lip and first-named flange, said hood further including diagonal side portions and flanges integral with said side portions, the last-named flanges being engageable between the second-named flanges, and means for detachably securing said last-named flanges.

JOSEPH P. MALLOY.
